FOREIGN PATENT DOCUMENTS

WO WO 1990/011945 10/1990

Primary Examiner — Lauren R Calve(74) *Attorney, Agent, or Firm* — Fish & Richardson P.C.(57) **CLAIM**

The ornamental design for a hang strap, substantially as shown and described.

DESCRIPTION

FIG. 1 is a front perspective view of a hang strap, showing our new design.

FIG. 2 is a front view of the hang strap of FIG. 1.

FIG. 3 is a back view of the hang strap of FIG. 1.

FIG. 4 is a left side view of the hang strap of FIG. 1.

FIG. 5 is a right side view of the hang strap of FIG. 1.

FIG. 6 is a top view of the hang strap of FIG. 1; and,

FIG. 7 is a bottom view of the hang strap of FIG. 1.

The broken lines illustrate portions (stitch lines) of the hang strap that form no part of the claimed design.

1 Claim, 4 Drawing Sheets(56)
